CLAIM

The ornamental design for a food draining insert for package, as shown and described.

DESCRIPTION

FIG. 1 depicts a perspective view of a food draining insert for package within a container.

FIG. 2 depicts a perspective view of a food draining insert for package.

FIG. 3 depicts a top view of a food draining insert for package; and,

FIG. 4 depicts a side view of a food draining insert for package.

In the drawings, the broken line showing of a container depicts environment and forms no part of the claim.
